CIGARETTE

Edward Oldroyd Whiteley, New York, N. Y.

Application March 10, 1939, Serial No. 260,966

3 Claims. (Cl. 131—4)

This invention relates to cigarettes and has for its principal object an improved cigarette in which the ash will not tend to flutter off and fall over the floor and one's clothing as the cigarette is burned. Other objects and advantages of the invention will appear in the following description.

In the drawing, the figure is a greatly enlarged side view of a partially burned cigarette, incorporating my invention, and with a portion of the unsmoked cigarette broken away to reveal the fiber within.

In further detail 1 designates the outer paper wrapping of the cigarette, 2 is the burned portion after about half of the cigarette has been smoked, 3 is the ash supported within a network of partially fused glass fibers 4, the tobacco is designated 5, while the unfused glass fiber is designated 6 both mixed in the tobacco 5 and incorporated in the paper wrapper 1.

Briefly described my improvement in cigarettes comprises the admixture with the tobacco of inert materials adapted to strengthen or stabilize the ashes as they are formed so that they will be to a considerable degree self-sustaining, and need therefore only occasionally be broken off to deposit in an ash receptacle, and will not tend constantly to flick off and fall or blow off with the slightest draught of air. In addition to the above I preferably strengthen the ash of the paper wrapper so that it forms an additional external support for the ashes of more or less continuous though porous tubular form. As the stabilizing elements which I use both in the tobacco as well as in the paper wrapper are inert and sterile, and not adapted to be consumed by the heat of the burning tobacco and paper which forms the combustible structure of the cigarette, there is no change of flavor or aroma of the cigarette in the smoking.

As an ash strengthening material for admixture with the tobacco preparatory to forming the cigarettes I may use any non-toxic fibers of cellulose which have been suitably purified to remove flavors and which have been rendered fire-proof as by treating with fire-proofing liquids or emulsions such as colloidal solutions of magnesia, sodium silicate, preferably in combination with tars or oils distilled or extracted from natural tobacco leaf, such solutions being first passed through a homogenizing machine at pressures up to several thousand pounds per square inch to give them stability, and thereafter dipping the fibers therein to thoroughly wet the same and removing the surplus by light centrifuging.

I may also use in admixture with the above fibers, or admixture with the tobacco only, fibers of spun glass or roasted and purified asbestos. If glass fibers are used I prefer to use a glass made from potassium and calcium silicates with added oxide of boron so as to yield a glass fiber when spun which will have a very low coefficient of expansion, as well as considerable flexibility and resistance to heat, so as to contribute these properties to the ash as a whole.

The glass fiber is, before thorough admixing with the tobacco, pre-treated by giving it a thin coating of a hygroscopic substance such as glycerine, licorice extract or admixtures, and preferably with a small percentage of extract of natural tobacco. This coating prevents displacement or shaking out of the glass fibers. The fiber may be either sprayed or dipped and centrifuged and the treated glass fiber is admixed to the extent of about 10% with the tobacco, the proper amount depending to a certain extent on the natural stability of the ash of the particular tobacco used, it being desirable to use no more of the strengthening fiber than required to give reasonable stability to the ash.

I find by tests of cigarettes made as above described that they may be smoked to half or more of their length without the stabilized ash falling off, thus adding greatly to the convenience and enjoyment of smoking. The glass fibers appear to fuse slightly at points of touching so as to make a network of supports throughout the ash. The same treatment may be applied to cigars, though not quite so conveniently as the filler material used in cigar making is not so finely divided and mixed as it is in cigarette making.

As before mentioned, I may also strengthen the paper wrapper of the cigarette with the glass or other fire-proof fibers. In the process of manufacturing the cigarette paper-plus glass fiber I use any workable system of adding the glass fiber to the cellulose pulp. I give two examples:

(1) The glass fiber is added to the cellulose pulp by feeding it slowly during the slow rotation of the mixing paddles or beaters, to avoid breaking down the fiber, this operation being done immediately before the run is made on to the wire screen former.

(2) The glass fiber is fed evenly from a revolving conveyor as a thin layer to the cellulose pulp immediately where the pulp runs on to the wire former at the wet end.

In both methods the fine glass fiber is forced into the formed pulp under pressure of the hot rolls and becomes part of the composite mass of

cellulose pulp and glass fiber, emerging from the pressure of the hot rolls in the form of sheets of composite paper. I have found that about 15% by weight of the glass fiber gives a satisfactory result.

In considering my invention as above set out it should be noted that while I have mentioned several fire-proof fibers as suitable for the purpose, any other fibers having similar properties may be used without departing from the spirit of the invention as included within the scope of my appended claims.

My use of the word "cigarette" in the claims is also intended to include a cigar in which my invention is incorporated.

I claim:

1. A cigarette provided with a filling of tobacco admixed with inert fire resisting fibers adapted

to strengthen the ash when the cigarette is burned, said fibers coated with an adhesive substance adapted to prevent displacement of said fibers.

5 2. A cigarette provided with a filling of tobacco admixed with inert fire resisting fibers adapted to strengthen the ash when the cigarette is burned, said fibers coated with an adhesive substance including licorice adapted to prevent displacement of said fibers.

10 3. A cigarette provided with a filling of tobacco admixed throughout with glass fibers, said glass fibers having a fusing point causing them to soften and adhere slightly at points of touching due to heat evolved when the cigarette is smoked, and an adhesive substance holding said glass fibers from displacement in the tobacco.

EDWARD OLDROYD WHITELEY.
